Samuel Thomas Walkup Inventor

UNITED STATES PATENT OFFICE.

SAMUEL THOMAS WALKUP, OF NEW YORK, N. Y.

CAR DOOR.

Application filed October 20, 1921. Serial No. 509,122.

To all whom it may concern:

Be it known that I, SAMUEL THOMAS WALKUP, citizen of the United States, and resident of New York city, in the county of New York and State of New York, have invented certain new and useful Car Doors, of which the following is a specification.

My invention relates to improvements in a car door, and particularly to such a door of an elevated or subway railway car, and it consists in the combinations, constructions and arrangements herein described and claimed.

An object of my invention is to provide electrical means for opening or closing a door of a railway car.

A further object of my invention is to provide electrical means for opening or closing a railway car door from a station platform.

My invention is illustrated by the accompanying drawings forming part of this application.

Fig. 1, is a diagrammatic view of a usual elevated city railway car with means for opening or closing a door or "gate".

Fig. 2, is a detail of electrical means for opening or closing a door of a car.

Fig. 3, is a diagrammatic view of a usual subway city railway car with sliding door and of means for opening or closing said door.

Fig. 4, is a detail of a sliding car door operating means.

1 is a railway car, and 1¹, and 1¹¹, are adjoining cars, 2—2 are doors or "gates" of the cars rigidly mounted on vertical shafts 4, which extend through the platform of the car. To the lower end of shaft 4, is attached a short arm 20 on which link 19 is slidably mounted. Link 19 is pivoted to 17 the core of a solenoid 3, which when energized opens the door or "gate" as shown at dotted line, 2, and when it is de-energized, expansion spring 18 returns core 17 to normal position and closes door or "gate" 2. Solenoid 3, is caused to open the door or "gate" by an operator, located preferably on the platform of a station directly alongside a railway car, by pressing button 14, against resistance spring 15, into contact with conductor 16, thereby making an electric circuit through wire 13, third electric rail 10, shoe 6, wire 7, with resistance, solenoid 3, wire 8, shoe 5, fourth rail conductor 9, wire 13¹, which is attached to push button 14.

When the operator releases spring push button 14, the solenoid is de-energized and expansion spring 18 returns the core of solenoid to normal position which causes door 60 or "gate" to be closed.

A, illustrates a subway car with sliding doors B—B. A¹ and A¹¹ are adjoining cars. C is a rack attached to door B and meshed with gear D operated by worm E mounted 65 on rotor of motor F, attached to the bottom of the railway car. An operator preferably on platform O, alongside the car, pushes button S, closing an electric circuit through resistance wire Q, third electric rail K, shoe J, wire M with resistance at T, motor F, wire N, shoe G, fourth rail H, wire R attached to push button S. It is obvious that the car door is closed or opened according to direction of rotation of rotor of motor, 70 and that it is desirable to use a reversible motor and controller which are well known to the art and unnecessary to show and describe herein.

I do not limit my invention to the precise 80 mechanism and combinations of devices herein described and shown as many variations may be made therein without departing from the spirit of the invention or sacrificing its principal advantages.

What I claim is new and desire to secure by Letters Patent is:

1. The combination with a track and a car thereon provided with a door, of a fixed conductor bar alongside the track at a station, a power rail alongside the track to furnish electric driving energy, shoes making contact with said bar and rail, respectively, and carried by the car, an electrically actuated device for operating the door, conductors connecting said device to both said bar and rail through said shoes, a conductor leading back from the bar to the power rail, and a manual switch in the circuit through said device.

2. The combination with a track and car thereon provided with a door, of a solenoid for operating the door in one direction, a spring for moving the door in the contrary direction, conductors making circuit through said solenoid from a common third power rail and back to the latter and a manually operable switch interposed in the circuit.

3. The combination with a track, a power rail alongside the track, a fixed conductor bar alongside the track at stations, a car

upon the track carrying shoes in position to make contact with both said rail and bar, respectively, an electrical door opening device connected with both said shoes, a conductor leading back from said bar to said rail, and a manually operable switch in said conductor.

4. The combination with a railway track and power rail and conducting bar parallel thereto, a car upon the track provided with shoes in position to make contact with the rail and bar, respectively, an electrical car

door actuating device, conductors forming a circuit from said rail through said device and bar back to said rail, and a manual switch fixed at a station and arranged to open and close said circuit. 15

In witness whereof, I have signed my name to this specification in the presence of two subscribing witnesses.

SAMUEL THOMAS WALKUP.

Witnesses:

A. F. WORTMAN,
FREDERICK STEFFENS.
